Application April 24, 1939, Serial No. 269,666

4 Claims. (Cl. 196—56)

This invention relates to the art of converting gaseous hydrocarbons into high anti-knock motor fuels, and more particularly to a process in which highly heated gaseous hydrocarbons assist in a destructive distillation of solid pyrobituminous material with mutual benefit to the reaction of the gaseous hydrocarbons and to the treatment of the solid material.

It has already been proposed to destructively distill raw coal in the presence of petroleum oils undergoing destructive distillation at ordinary cracking temperatures, but such processes have not been adopted commercially on account of their low yields of motor fuels or other valuable products, when the products are evaluated in comparison with the cost of handling the coal and the difficulties of recovering the desired low boiling distillates from the tarry mixtures formed.

Some of the main objects of this invention are: to increase production of high anti-knock liquid fuels from pyrobituminous solids, e. g. coals, subjected to destructive distillation in a practical and economical manner; and to effectively utilize pyrobitumens undergoing carbonization, their products, and addition agents to promote polymerization of gaseous hydrocarbons with reduced tar formation.

It is within the contemplation of this invention to effect a complete liquefaction and gasification of carbonaceous material in coal, thus extending the utility of the process further to production of water gas and an inorganic residue suitable for use in catalytically cracking higher boiling hydrocarbon vapors to gasoline hydrocarbons.

A major advantage obtained by proper control and combination of the various reactions according to the present invention is obtained in the increased yield of more valuable products with economy of heat energy input, handling of materials, and exhaustive use of materials treated.

Other objects and advantages will become apparent from the following description.

To obtain the desired results, whether in a batch or continuous treatment, the coal or solid pyrobituminous material is transformed in stages. The batch procedure is cyclically carried out in apparatus similar to gas generators in design.

For conducting an efficient continuous treatment the solid material is preferably used in a finely divided form.

The main process steps comprise a rapid preliminary heating of the solid fuel with limited vaporization of volatile constituents to bring the solid fuel to a temperature above 800° F., so that

5 the solid fuel is past its plasticizing or fusion stage. Following this preheating, the solid fuel in a dry state is contacted with reactive gaseous hydrocarbons at a sufficiently high temperature to promote decomposition of the solid fuel into gaseous hydrocarbons and solid carbonized residues; simultaneously, gaseous hydrocarbons introduced for heating the solid fuel are induced to undergo polymerizing reactions. Resulting carbonized solid residues may then be treated to completely gasify their remaining non-volatile carbonaceous components under conditions which leave a highly adsorbent ash of inorganic substances, suitable for use in catalytically splitting higher boiling hydrocarbon vapors into gasoline hydrocarbons. In this manner the process is capable of producing a wide range of volatile products without waste of heat or materials.

20 For a better understanding of the invention the following illustrative example is given, other modifications being within the purview of this invention.

25 A bed of dry coal, for example, is subjected to a batch treatment by first treating the coal to a predetermined high temperature with a hot blast of relatively inert gases, such as flue gases or air blow combustion products, which may contain a small amount of free oxygen or air. Coal particles of the bed are sufficiently large so as not to be swept away by the blast of gases, but small enough for rapid heat conduction, when they are able to pass a 4 mesh screen. This preheating period is restricted so that the coal is brought rapidly to a temperature above 800° F., before it begins to undergo substantial destructive distillation, in order to avoid the formation of tarry liquids, which are produced more readily when the coal tends to fuse into a plastic mass. This plasticizing of the coal occurs principally when 30 the coal is heated in the range of 600 to 800° F., but it can be overcome by supplying the blast of heating gases at an adequate rate of flow and a high temperature. The heating gases are supplied preferably at a rate above 10 cu. ft. per second per pound of coal and at a temperature above 850° F., these conditions varying in accordance with the amount of preheat retained by the coal from a drying treatment, quality and size of coal, and other governing factors. With the temperature of the coal brought to about 800° F., highly heated gaseous hydrocarbons from a high heat 35 resistant alloy heating coil are led into the hot coal at a coil outlet temperature of about 1000° F., to about 1300° F., in place of the blast of preheating gas. Thus begins the period of coal de-

composition and carbonization to form coke. While supplying heat for the carbonization, the highly heated reactive hydrocarbon gases, largely composed of olefins and free hydrocarbon radicals, are given opportunity to polymerize and react with gaseous products from the coal in the presence of the coke thus being produced. The vaporous products withdrawn from the reaction zone comprise valuable high anti-knock motor fuel hydrocarbons including aromatics, alkylated aromatics, naphthenes, alkylated naphthenes and other complex organic motor fuel compounds substantially free from tarry bodies.

After termination of coal carbonization, as indicated by substantial decrease in distillate yield, the resulting coke bed is ready for an air blowing to heat lower layers of the coke bed to incandescence, generally with a short preceding purge by superheated steam. To avoid clinkering of ash residue the temperature of the coke bed is maintained below maximum temperatures of about 1800° F. to 2500° F.; this can be partly regulated by injecting steam with the air into the coke bed.

Hot products from the air blowing step contain predominately carbon dioxide, nitrogen, and steam, a small amount of carbon monoxide and excess oxygen. With high exit temperatures, these products are very useful for initiating distillation of a new coal bed through rapid pre-heating past the plasticizing stage of the coal, although heat recovery may be made from them in some other manner.

After the temperature of the coke bed has been brought to a high degree favorable for carbon monoxide formation, i. e., about 1500 to 2000° F., superheated steam is passed therein to produce water gas, until the carbon monoxide and hydrogen yield drops and a substantial portion of the coke bed has been gasified, leaving an ash residue. Carbon dioxide may be injected with the superheated steam to produce water gas.

The remaining ash and any residual coke may then be used while in heated condition to serve as a contact mass for dry hydrocarbon vapors led in from a cracking coil at a coil outlet temperature in the range of about 800 to 950° F. In the form obtained, this contact mass functions to eliminate undesirable entrained tarry bodies and other impurities, also to favor increased yields of purified distillates by furthering the splitting reaction of higher hydrocarbons and promoting polymerization of normally gaseous hydrocarbons formed by the splitting reaction.

A number of the steps may be carried out efficiently with a continuous procedure to be more fully described in conjunction with the drawings. In the continuous procedure the coal or solid fuel is more advantageously first reduced to a pulverized condition by grinding until it is able to pass a screen of about 20 to 40 mesh, or finer.

It is also advantageous to agglomerate a powdered fuel with an adhesive material which upon being dried acts as an adsorbent and catalyst. Examples of substances useful in this capacity are silica gel, alumina gel, bentonite gel and similar inorganic substances which upon drying form refractory porous masses of large surface area. By heating and agitating these substances with the powdered fuel, agglomerated pellets are formed. These pellets are preferably reduced in size by a further grinding to particles fine enough to pass at least a 20 mesh screen, and these particles may be given an activation treatment by contact with inorganic acidic gases, such as oxides of phosphorus, oxides of sulphur, or chlorine.

The purpose of this activating treatment is to combine with the solid particles small amounts of a compound which can function to activate hydrocarbon compounds, to promote carbonization, and/or to reduce oxygenated compounds.

In the thus preheated and activated form the solid fuel particles when suspended in a stream of high temperature reactive hydrocarbon gases readily decompose to liberate volatile hydrocarbons, leaving a small amount of residual carbon and ash. The activated coal particles undergoing decomposition behave as a highly efficient promoter for the polymerization of gaseous hydrocarbons while furnishing active molecules or free radicals which conjointly are subjected to the polymerization reaction.

Suitable apparatus for the described procedures are shown in the accompanying drawings in which:

20 Figure 1 illustrates diagrammatically in cross-section a preferred type of gas generator apparatus for use in the batch procedure;

25 Figure 2 illustrates diagrammatically in cross-section a preferred means for the continuous treatment of powdered coal.

Referring to Figure 1, the apparatus in its simplest form may consist in one or more gas generators, A and B, together with useful appurtenances. The generators have connections to vapor and gas product recovery systems of well known types used in conjunction with gas plants and petroleum refining units. For maintenance of service, preferably two or a plurality of generators are used conjointly. A number of generators may be used also in series. An efficient cooperation is obtained when the generators perform in alternate periods of the treatment cycles.

The generator or reaction apparatus in its 40 simplest form is constructed merely of a steel shell 1 lined with fire brick 2, provided with grate 3 or similar means for supporting a coal bed 4, a coal charging means 5 with a closure therefor 6, ash pit 7 beneath the grate 3, ash discharge means 8, and with devices for admitting and withdrawing gaseous fluids.

Each generator is provided with conduits 9 through which hot combustion gases are supplied to the underside of coal beds 4 and with outlet 50 conduits 10 and 11 for removal of gaseous fluids. Inlet pipes 12, 13, and 14 are disposed at the bottom of each generator for injection of hydrocarbon reactants, steam, and air respectively. Conduits 9 and 10 are interconnected through 55 a manifolding conduit 15 whence they branch for diverting the flow of hot gases withdrawn from one generator into a second generator. This arrangement accomplishes a desired passage of hot gases, for example, when hot gases withdrawn from generator A through offtake conduit 10 having valve 16 open, valves 17, 18, 19, 20, 22 and 24 being closed, are passed via manifold conduit 15 into the base of generator B through the open valve 21 of conduit 9, flue outlet 11 from generator B being open. The conduits 11 lead through valve 17 or 23, whichever one is open, from the generators to a flue gas main which may lead to any conventional heat recovery system (not shown). With valves 17 and 65 23 closed conduits 11 lead gaseous hydrocarbon products or water gas to their respective recovery systems (not shown) through valved connection 25 and 26.

To illustrate the operation of the process with 75 reference to the apparatus described in Figure 1,

for the initial stage of the process hot combustion products from a furnace or from an alternate generator being used in an air blowing period of its cycle may be injected through conduit 9 into a fresh bed of coal 4 charged into generator A. Hot combustion products may otherwise be produced below the coal bed 4 in generator A by combustion of hydrocarbons with air injected through inlets 12 and 14. Hot combustion gases preferably containing some free oxygen at a temperature of about 900° to 1800° F., are blasted through the coal bed to quickly heat the coal to above 800° F., and thereby initiate coal distillation into high temperature products such as volatile cyclic hydrocarbons boiling in the motor fuel range. The waste heating gases are withdrawn through an open connection to conduit 11. This preheating is preferably limited to separate less than 15% of the volatile matter in the coal.

In the second stage of the operation the high temperature distillation of the coal is maintained at a temperature in the range of about 1000° to 1300° F., or higher, when highly heated hydrocarbon gases in place of the combustion products next are lead into the coal bed from inlet 12. These highly heated hydrocarbon gases are preferably reactive products resulting from a thermal cracking or a dehydrogenation of refinery or field gases, such as natural gas. In general, the highly heated reactive hydrocarbon gases are obtained from hydrocarbon mixtures composed largely of ethane, propane, butane, etc., by a high temperature conversion which transforms substantial amounts of the paraffinic hydrocarbons into straight and branched chain olefins.

The following table shows the olefin content of a typical product from thermally cracked paraffinic hydrocarbons:

	Percent
Ethylene	7
Propylene	21
Normal butylene	13
Isobutylene	8
Amylenes	5

The activated hydrocarbon gases leaving a pyrolysis coil at an outlet temperature in the range of about 1000° to 1300° F., and a super-atmospheric pressure of about 200 to 1500 lbs. per sq. in. gage, are passed under substantially the same conditions, with adjustment of pressure for the capacity of the system, into the preheated coal bed. In contact with the coal and carbonization products being formed through direct heat transfer from the gases, the reactive hydrocarbon gases are given time and inducement to undergo polymerization. Volatiles released from the coal react as nascent hydrocarbons while porous coke being formed acts as a catalytic adsorbent contact mass. Hydrocarbon products comprising motor fuel polymers, aromatic volatiles, and fixed gas are recovered by being withdrawn through conduit 11 to the open connection 26 which leads to any suitable fractionating and motor fuel distillate recovery system.

When the solid fuel has been exhausted in the polymerization and distillation, as indicated by the decline in yield, the next stage of the cycle is started preferably after a short purging of residual volatiles from the coke bed by a blast of steam injected from valved inlet 13. Following this final removal of volatile hydrocarbons, the coke bed is blown with air from valved inlet 14

to cause combustion in the lower part of the bed, resulting in elevating the temperature of the coke bed substantially to incandescence.

5 The hot combustion products formed from the burned coke are withdrawn from generator A through conduit 10 at a temperature above 1500° F., and at this temperature may be passed directly through manifold 15 and inlet 9 to the base of generator B for use as a hot blast of gases to preheat a fresh charge of coal therein.

10 At incandescence the elevated temperature of the coke is conducive to water gas formation, and in the following stage, steam is injected from valved inlet 13, about .25 to about 2 pounds of steam being used per pound of coal initially introduced, the coke bed being, for example, about twice the depth of the ash layer upon which it rests.

15 The water gas products may be removed from generator A through conduit 11 to an open connection 25 which leads to a recovery and storage system. As an alternative, the water gas may be passed as a preheating gas first through a coal bed in another generator in series.

20 25 A final stage of treatment which may be used in generator A is obtained by directing hot hydrocarbon vapors from a vapor phase cracking coil through the ash bed remaining from the water gas generation. The hydrocarbon vapors are introduced into the generator by valved inlet 12 which may be joined alternately with a conventional type of cracking coil for high boiling hydrocarbon vapors or with the pyrolysis coil for the hydrocarbon gases.

30 35 Following the preheating of the coal bed in generator B the same cycle of operation is performed therein. The hot combustion gases produced during the air blowing stage being used similarly, as described, to preheat a fresh charge of coal in generator A.

40 45 A convenient modification and additional features of the invention are best described by reference to Figure 2, which illustrates means for continuously pretreating the solid fuel or coal before it is reacted with high temperature decomposition products of normally gaseous hydrocarbons and means for continuously carrying out the joint coal distillation and gas polymerization reaction.

50 55 In apparatus shown in Figure 2, coal in pulverized and dried condition, also substances such as the adhesive gel materials mentioned, may be continuously fed from hopper 29 by a rotating discharge means 30 into the heating kiln 31. A rotating helical scraper 32 is disposed in the kiln for mixing the coal with adsorbent substances such as the gels mentioned, for exposing the coal more effectively to a blast of hot combustion gases from inlet 33, and for conveying the heated substances through the kiln to outlet chute 34. The hot combustion gases are used in the manner described with reference to Figure 1 for rapidly heating the pulverized coal to above 800° F. External heating means (not shown) may be provided surrounding the kiln for obtaining the desired elevated temperatures in preheating the coal. Waste heating gases are removed from the kiln by outlet 35. Dropping from the chute 34, the preheated powdered coal or agglomerated

60 65 mixture thereof with adsorbent material may be then passed through a sealed roll grinder 36 for maintaining the fineness of the material. The pulverized material is then passed into hopper bin 37, whence it is fed into the reaction tube 38 continuously in regulated amounts by measur-

ing and rotating discharge device 38. The measuring device 38 may be provided with means 48 for supplying a gaseous activating compound to the pulverized material, such compound being as an acidic inorganic gas as described.

The pulverized material becomes suspended in the stream of hot gaseous products evolved by the pyrolytic treatment of gaseous hydrocarbons passed through coil 41 disposed in furnace 42. Reaction tube 38 which may be of any length adequate for completion of the reaction terminates in the separator 43. By tangential injection and through the use of baffles 44, an efficient separation of suspended solids from the gasiform fluid products is effected. Separated gaseous products may be further freed from suspended solids by filtering through a bed of massive solid material, such as large pieces of coke, clay, or siliceous material in container 45, on their passage through line 46 leading to fractionator 47. Fractionator 47 is provided internally with the usual bubble cap plates or similar devices for obtaining fractional condensation and with an overhead outlet 48 leading to a condenser coil 49 terminating in receiver 50. Fractional condensation of vapors is controlled in 47 to collect a motor fuel distillate in receiver 50, which acts as a gas separator. Fixed gases from receiver 50 and reflux from fractionator 47 may be recycled in the usual manner. The solid reaction particles which precipitate in separator 43 form a bed of finely granulated coke at the bottom thereof. Superheated steam from spray inlets 51 surrounding the separator 43 may be injected near the base to drive residual volatiles from the solid particles. At the bottom of separator 43 is disposed a rotating means for continuous removal of the coked particles which may be used as a powdered fuel for heating purposes or in other reactions, as in the production of water gas with recovery of the uncombustible adsorbent material for use in a subsequent catalytic process, such as in a hydrocarbon cracking process.

A particularly beneficial embodiment of the invention consists in accomplishing the polymerization of normally gaseous olefins to normally liquid hydrocarbons in the presence of a solid carbonaceous fuel combined with certain inorganic compounds capable of promoting desired reactions. It has been found that inorganic compounds characterized by both hygroscopic and acidic properties have tendencies to become adsorbed by solid carbonaceous materials apparently uniting therewith in the form of compounds or complexes. At any rate the substances produced by combining these types of inorganic compounds with pyrobitumens or the calcined products, such as are formed in the preheating treatment to which coal or other pyrobituminous materials are first subjected in accordance with the present invention, effectively promote the release of volatile hydrocarbons from the solid fuel and induce polymerization of normally gaseous hydrocarbons in their presence to liquid hydrocarbons as indicated by resulting yields of high anti-knock gasoline fuels.

The types of substances formed when coal is rapidly calcined to above 800° F., with limited loss of volatile matter so that carbonaceous material of the coal is transformed into a substantially solid coked product, for convenience termed solid pyrobitumens, when treated with the hygroscopic and acidic compounds, are diffi-

cult to analyze. However, with the oxides of phosphorus, organic compounds present in the calcined coal may be said to become phosphated even though the phosphorus is considered to exist in several states of oxidation under the reaction conditions. For example, even if elementary red phosphorus or lower oxides of phosphorus are used some oxidation may occur at the elevated temperatures with the presence of oxygen compounds to produce higher oxides and on the other hand, higher oxides of phosphorus tend to be reduced as they react together with hydrocarbons or carbon monoxide. These factors establish the likelihood that the phosphorus oxides regardless of their initial composition ultimately become altered so that the phosphorus is combined with oxygen in ratios corresponding to the following compounds:

PO_3 and its polymers P_2O_4 , P_4O_6 and the like in equilibrium with P_2O_5 or its polymers.

In a similar respect oxides of sulfur used to activate the calcined coal may undergo changes of oxidation or reduction under the reaction conditions and accordingly be said to either sulphonate or sulphate the organic compounds present in the solid phase during the destructive distillation of the pyrobitumens contacted with the reactive hydrocarbon gases undergoing polymerization.

Anhydrous metal halides, particularly aluminum chloride, although other Friedel and Crafts type catalysts may be used including halogen compound of various other metals e. g., tantalum, tin, antimony, etc., appear to form various complexes with the solid phase pyrobitumens and similarly act as a promoter. The pyrobitumens may be additionally chlorinated and used as such or with a metal halide acting as a hygroscopic acidic compound.

Obviously each of the particular activating compounds will have its own peculiar action in causing the pyrobitumens to become decomposed and in bringing about interaction between the reactive hydrocarbon compounds brought into their presence. In some cases it is desirable to use a mixture of the activating compounds, for example, both oxides of sulphur and phosphorus.

Commercial adaptations of the process have been well exemplified in both batch and continuous treatments of olefinic gases conjointly with solid carbonaceous fuels for the production primarily of high anti-knock liquid hydrocarbon fuels.

To summarize, the principal products obtainable by treating solid carbonaceous fuels in accordance with the described process are as follows:

1. High octane number motor fuel ingredients composed of gaseous olefin polymers and cyclic hydrocarbons derived from destructive distillation of solid fuels.

2. A high pressure water gas of high heat content suitable for use in syntheses involving hydrogenation of carbon monoxide or for use as fuel.

3. The production of a valuable powdered fuel.

4. The formation of an efficient catalyst for hydrocarbon conversions including polymerization and splitting reactions.

5. While specific embodiments of the invention and systems for carrying them into practice have been explained by way of illustration, it is to be understood that this invention is not to be confined by the exact steps, pressures, temperatures, velocities, proportions, materials or particular

devices mentioned herebefore as typical or representative. For instance, various solid carbonaceous fuels from which volatile hydrocarbons can be derived by destructive distillation can be considered as equivalents of coal, such as oil shales, lignite and various types of coals. Various other devices, materials and conditions for securing optimum results may be utilized as needed or desired.

Having described our invention what we claim and desire to secure by Letters Patent is as follows:

1. A process for producing liquid hydrocarbons from solid carbonaceous fuel under the influence of gaseous hydrocarbons undergoing polymerization, which comprises calcinating said solid carbonaceous material agglomerated with a solid inorganic adsorbent gel in a finely divided form to above 800° F. to convert the carbonaceous material into solid pyrobitumens, separately heating a stream of normally gaseous hydrocarbons under a superatmospheric pressure to a temperature in the range of about 1000 to 1350° F. for a time sufficient to activate the hydrocarbons by dehydrogenation, mixing said solid pyrobitumens resulting from the calcination with the thus activated gaseous hydrocarbons to effect polymerization of the hydrocarbons and destructive distillation of the solid pyrobitumens in a dry solid state, removing vaporous reaction products, and condensing a gasoline motor fuel therefrom.

2. A process for producing liquid hydrocarbons from solid carbonaceous fuel under the influence of gaseous hydrocarbons undergoing polymerization, which comprises calcinating said solid carbonaceous material in a finely divided

- 5 form to above 800° F. to convert the carbonaceous material into solid pyrobitumens, activating said solid pyrobitumens by treatment with a hygroscopic acidic inorganic substance, separately heating a stream of normally gaseous hydrocarbons under a superatmospheric pressure to a temperature in the range of about 1000 to 1350° F. for a time sufficient to activate the hydrocarbons by dehydrogenation, mixing said solid activated pyrobitumens with the thus activated gaseous hydrocarbons to effect polymerization of the hydrocarbons and destructive distillation of the solid pyrobitumens in a dry state, removing vaporous reaction products, and condensing a gasoline motor fuel therefrom.
- 10 3. A process of polymerizing normally gaseous olefins to produce normally liquid hydrocarbons which comprises subjecting said olefins in the vapor phase under polymerizing conditions to the action of a calcined pyrobituminous material agglomerated with a solid inorganic adsorbent gel and activated with a hygroscopic inorganic compound while said calcined pyrobituminous material undergoes dry distillation.
- 20 4. A process of polymerizing normally gaseous olefins to produce normally liquid hydrocarbons which comprises subjecting an olefin containing gas in the vapor phase under polymerizing temperatures and pressures to the action of pyrobitumens agglomerated with an adsorbent siliceous material and treated with an oxide of phosphorus said pyrobitumen being partially distilled and undergoing carbonization in a dry solid condition.
